AUDIO FREQUENCY TRANSFORMER.

Application filed February 21, 1927. Serial No. 169,809.

This invention relates to transformers and more particularly to transformers for coupling vacuum tubes for amplifying frequencies within the audible range.

5 Heretofore transformers for coupling vacuum tubes in audio frequency amplifiers for use in musical reproduction have not amplified efficiently on low frequencies or low notes; have been unable to respond satisfactorily to frequencies or notes of the order of 10 50 cycles or less; or have caused distortion to those frequencies or notes which they did amplify; and many such transformers have possessed two or more of these serious disadvantages.

I have discovered, however, that it is possible to construct a transformer which will amplify frequencies or notes in the musical scale and as low as about 50 cycles with practically no attenuation; which will respond satisfactorily to frequencies or notes of from about 50 cycles down to about 16 cycles; which will respond effectively to frequencies of from about 16 cycles to about 5 cycles; 25 that is, well above 50% of the maximum amplifications at any frequency; and which will also cause substantially no distortion of the wave form of a current or note within the limits of the musical scale and its necessary 30 harmonics, that is within the useful musical scale. Since it is well known in the art that frequencies from 16 cycles to 50 cycles are at least as important in giving naturalness and body to music and voice reproduction as the 35 higher frequencies, it will be seen that my improved transformer is greatly superior to the prior art devices.

Many of the prior art transformers also possessed resonant points above the useful 40 musical scale but within audibility and consequently amplified static and other disturbances unnecessarily. My improved transformer, however, has a marked tendency to suppress frequencies above the useful musical 45 scale and consequently greatly diminishes static and other outside disturbances.

Prior art transformers, with which I am 50 familiar, have high amplification constants as compared with the constant of my transformer. Such prior art transformers often set up sustained frequencies or oscillations 55 within the audible range between the loud speaker and the detector tube, caused by the mechanical vibration of the detector tube, probably at some resonant point. Special

sockets have been devised to prevent such mechanical vibration. With my transformer, however, no such sustained frequencies are set up due, I believe, to the absence of any such resonant point, and hence no 60 special sockets or other similar apparatus is required. Moreover, by reason of the relatively low amplification constant of my transformer, it is possible, when the transformer is used in conjunction with a receiving 65 set, to operate the set at its maximum operating efficiency without loss of selectivity or tone quality necessarily caused by the detuning of the set.

With my transformer it is possible to control the variation of amplification or frequencies or notes within the entire musical range and its necessary harmonics to within a few percent, that is to cause these frequencies to be amplified in the desired proportion; and to amplify both the small currents and large currents substantially the same number of times. This is true whether the amplification is considered in either of two ways; first a single cycle, and second, a 70 series of cycles. In the former case is meant substantial absence of wave form distortion; that is a current input in the primary winding tending to rise and fall at a uniform rate 75 will cause the voltage in the secondary winding to rise and fall at the same rate as in the primary. In other words, the transformer will not distort the signal wave form in transferring it from one tube to the next tube. In the latter case, a series of cycles or notes 80 whose amplitudes are weak or small will be amplified in the same proportion as a series of cycles or notes whose amplitude variations are large. For these reasons, my transformer 85 may be said to possess substantially linear 90 characteristics.

A transformer possessing the foregoing 95 properties may be briefly described as consisting, in a preferred form, of a coil comprising primary and secondary windings of about 100 a one to one ratio with about 6,000 turns of wire in each, the wire of the primary being of such size as to carry the current necessary for the power tube connected to the primary circuit and the wire of the secondary being 105 of about size 40, in combination with a core of iron or other material of high permeability whose effective cross sectional area is equivalent to at least about two square inches of 110 standard silicon transformer steel and whose

average magnetic path is about 4 or 5 inches. Certain variations from the foregoing preferred sizes and dimensions may be made but with correspondingly varying results.

5 For example, the ratio of primary to secondary may vary between about 2 to 1 and about 1 to 2 but the distortion increases each way from the one to one ratio. The turn value may vary from about 3500 to about 8500 with 10 distortion increasing toward each limit, but not being particularly marked or objectionable for considerable variations either side of the 6000 turns mentioned. The iron core may vary in cross sectional area from about 15 $1\frac{1}{2}$ sq. inch to the limit of practicability with slightly improved results above 2 square inches. The average magnetic path is kept as short as is practicable. When a core material is used having a permeability different 20 from the iron above referred to, the cross sectional area of such cores should be varied correspondingly so as to be equal in effect to a standard iron core having an effective magnetic length of four or five inches and a cross 25 sectional area of above about one and a half square inches and preferably about two square inches.

It is well known that, in order to produce sensations of equal loudness to the ear of various frequencies within the musical scale and its necessary harmonics, signal amplitudes are required which vary inversely as the squares of the frequencies. Therefore, it is necessary in amplifying the low frequencies, 30 that means be employed to handle the necessarily large amplitudes of such frequencies. My transformer will handle such extra large signal amplitudes substantially without distortion. Because of this capability I preferably employ a power tube in each stage of 35 audio amplification, the transformer being capable of withstanding the necessarily large plate current when used as a coupling between two such power tubes. This property 40 of my transformer is traceable, I believe, not only to the specified ratio and turn value but also partly to the extremely large primary inductance which, in the preferred form of the device previously described, should exceed about 250 henries and may exceed 400 45 henries, both as calculated from the formula, in conjunction with the use of correspondingly increased voltage which should exceed about 250 volts with tubes capable of handling large signal variations.

By reason of the very large impedance and low resistance of the primary winding of my transformer, a loud speaker may be placed directly across the primary winding which 50 will advantageously operate to pass the direct current of the plate circuit of the power tube around the loud speaker, substantially without effecting the quality or volume of the signal applied to the loud speaker from the plate 55 circuit of the power tube, thereby eliminat-

ing the usual 2 microfarad condenser in series with the loud speaker.

Moreover, for this same reason complicated switching arrangements need not be used between stages when it is desired to shift the 70 number of stages of amplification in use as the loud speaker or other indicating device may be directly placed or plugged across the primary winding in any stage without noticeable loss of any kind due to such parallel 75 connection.

In the drawings forming a part of this specification and illustrating one form of apparatus embodying my invention and its characteristics;

Fig. 1 is a perspective view of a transformer with the cover removed.

Fig. 2 shows a curve sheet indicating the relative intensity of amplification of signal currents with variations in frequencies from 85 0 to about 4000 cycles per second, and

Fig. 3 shows a curve sheet indicating the relative increase in output of the secondary winding for linear increase of input in the primary winding.

In Fig. 1 the transformer is shown as including a core 2 of suitable material, such as iron, which may be built up of laminations 3 each of which is formed of two parts as shown, or may be formed of any desired number of parts; and a coil 4 of layer wound wire comprising primary and secondary windings.

In Fig. 2 I have indicated by curve 169 the property possessed by my transformer in amplifying signal currents at various frequencies, and by curves 168 and 170 the corresponding properties possessed by certain of the better transformers of the prior art which I have tested. It will be noted that the variations of these latter transformers are 100 greater than the variations of my transformer and also that those transformers are incapable of responding to frequencies between about 5 and about 50 cycles. It will be understood that the curves are not extremely accurate on the very low frequencies but these curves do indicate the relative values of the 105 respective transformers.

In Fig. 3 I have indicated by curve 174 the property possessed by my transformer of 115 producing an output in the secondary windings which varies uniformly with the input in the primary winding. Curves 172 and 173 show the corresponding properties possessed by the prior art transformers referred to 120 above. Since these curves indicate the amount of distortion produced, it will be seen that my improved transformer is markedly superior, in respect to its quality of reproduction, to these prior art transformers.

It will be understood that the foregoing detailed description has been given for the purpose of enabling those skilled in the art to practice my invention, and not for the purpose of limiting my invention thereto. Va- 130

rious changes may be made in the apparatus described in detail within the spirit of my invention, the scope of which is defined in what is claimed:

5. What is claimed is:—

1. An improved transformer for coupling vacuum tubes in audio frequency amplifiers comprising primary and secondary windings having a ratio of approximately one to one 10 and a turn value of about 6000; and an iron core having a cross sectional area of about 2 square inches and an effective magnetic length of about 4 or 5 inches.

2. An improved transformer for coupling 15 vacuum tubes in audio frequency amplifiers comprising primary and secondary windings having a ratio of from about 2 to 1 to about 1 to 2, and an iron core, the turn value of the winding being between 3500 and 8500 and the 20 area of the core being such as to cause approximately the same variation of output on the secondary as the variation in input in the primary, throughout the useful musical scale.

25 3. An improved transformer for coupling vacuum tubes in audio frequency amplifiers comprising primary and secondary windings having a ratio of from about 2 to 1 to about 1 to 2, and a turn value of about 6000; and an iron core having such a cross sectional area and effective magnetic length as, in conjunction with the said windings, will cause notes throughout the useful musical scale to be amplified substantially uniformly and will 35 cause the variation in secondary output to follow closely the variations in primary input.

4. An improved transformer for coupling 40 vacuum tubes in audio frequency amplifiers comprising primary and secondary windings having a ratio of approximately 1 to 1 and a turn value of between about 3500 and 8500; and an iron core having such a cross sectional area and effective magnetic length as in conjunction with said windings will cause notes 45 throughout the useful musical scale to be amplified substantially uniformly and will cause the variations in secondary output to follow closely the variations in primary input.

5. An improved transformer for coupling 50 vacuum tubes in audio frequency amplifiers comprising primary and secondary windings, having a ratio of between about 2 to 1 and about 1 to 2 and a turn value of between about 55 3500 and 8500, and a core, the transformer being capable of amplifying frequencies throughout substantially the entire useful musical scale and also of amplifying without serious loss of amplification frequencies as low as about 16 cycles.

6. An improved transformer for coupling 60 vacuum tubes in audio frequency amplifiers comprising primary and secondary windings having a ratio of approximately one to one

and a turn value of between about 4000 and 7000, and an iron core having a cross-sectional area of about two square inches and an effective magnetic length of about four or five inches.

7. An improved transformer for coupling 70 vacuum tubes in audio frequency amplifiers having substantially linear characteristics and comprising primary and secondary windings having a ratio of approximately one to one and a turn value of between about 3500 and 8500, and an iron core having a cross sectional area of about two square inches and an effective magnetic length of about four or five inches.

8. An improved transformer for coupling 75 vacuum tubes in audio frequency amplifiers having substantially linear characteristics and comprising primary and secondary windings, having a ratio of approximately one to one and a turn value of about 6000, and a core having an effective magnetic length of four or five inches and composed of magnetic material substantially equivalent to a standard iron core having a cross sectional area above about one and a half square

80 inches. 9. An improved transformer for coupling vacuum tubes in audio frequency amplifiers having substantially linear characteristics and comprising primary and secondary windings, having a ratio of approximately one to one and a turn value of between about 4000 and about 7000, and a core having an effective magnetic length of about four or five inches and composed of magnetic material substantially equivalent to a standard iron core having a cross sectional area above about one and a half square

95 inches. 10. An improved transformer for coupling 100 vacuum tubes in audio frequency amplifiers having substantially linear characteristics and comprising primary and secondary windings, having a ratio of from about two to one to about one to two, and a turn value of between about 4000 and 7000, and a core having an effective magnetic length of about four or five inches and composed of magnetic material substantially equivalent to a standard iron core having a cross sectional area of 110 above about one and a half square inches.

11. An improved transformer for coupling 115 vacuum tubes in audio frequency amplifiers comprising primary and secondary windings, having a ratio of from about two to one to about one to two and a turn value of about 6000, and a core having an effective magnetic length of about four or five inches and composed of magnetic material substantially equivalent to a standard iron core having a cross sectional area of about two square

120 inches. 12. An improved transformer for coupling 125 vacuum tubes in audio frequency amplifiers having substantially linear charac-

teristics and comprising primary and secondary windings, having a ratio of between about two to one and one to two and a turn value of between about 4000 and 7000, and a 5 core composed of suitable material of suitable magnetic length and cross sectional area, the transformer being capable of amplifying frequencies throughout substantially the entire useful musical scale and also of amplifying 10 without serious loss of amplification, frequencies as low as about 16 cycles.

13. An improved transformer for coupling vacuum tubes in audio frequency amplifiers comprising primary and secondary 15 windings, having a ratio of about one to one, and a turn value of about 6000, and a core of suitable magnetic material and suitable magnetic length and cross sectional area, the transformer being capable of amplifying 20 frequencies throughout substantially the entire useful musical scale and also of amplifying

without serious loss of amplification, frequencies as low as about 16 cycles.

14. An improved transformer for coupling vacuum tubes in audio frequency amplifiers comprising primary and secondary windings, having a ratio of between about two to one and about one to two and a suitable turn value, and a core having an effective magnetic length of about four or five inches 25 and composed of magnetic material equivalent substantially to a standard iron core having a cross sectional area of above about one and a half square inches, the transformer being capable of amplifying frequencies 30 throughout substantially the entire useful musical scale, and also of amplifying without serious loss of amplification, frequencies as low as about 16 cycles.

In testimony whereof I hereunto affix my 35 signature this 18th day of February, 1927.

JOHN A. VICTOREEN.
